UNITED STATES PATENT OFFICE.

BENJAMIN F. SUTTON, OF BROOKLYN, NEW YORK, ASSIGNOR TO HIMSELF,
RUSSEL PARKER, AND JAMES H. STEARNS, ALL OF SAME PLACE.

SYRINGE-TUBE.

SPECIFICATION forming part of Letters Patent No. 339,821, dated April 13, 1886.

Application filed January 25, 1886. Serial No. 189,568. (No model.)

To all whom it may concern:

Be it known that I, BENJAMIN F. SUTTON, of Brooklyn, in the county of Kings and State of New York, have invented a new and useful Improvement in Syringe Tubes or Conduits, of which the following is a specification.

My invention relates, generally, to the discharge tubes or conduits of syringes, and also to the bulbs which are comprised in such tubes, and which form a part of the conduit, and which may be considered as an enlarged portion of the tube. The invention is, however, more particularly intended for such syringe-tubes as are in their normal condition collapsed or in longitudinal folds, and which are expanded by the pressure produced in operating the syringe. Such collapsible tubes are shown and described in my United States Letters Patent No. 319,937, dated June 9, 1885, and their purpose is to provide for a continuous or nearly continuous discharge, the surplus or excess of liquid which is contained in the tube when expanded being expelled by the collapsible force of the tube when the bulb is released and allowed to recover itself. Such tubes or conduits operate most effectively when made of very thin and elastic india-rubber; and the object of my invention is to provide in them a re-enforcement by which their undue expansion to such an extent as would be liable to produce rupture will be prevented.

To this end my invention consists in an expansible tube or conduit having embedded in it or incorporated between its inner and outer surfaces a spirally-wound re-enforcement of thread or cord, the convolutions of which are widely separated or isolated from each other lengthwise of the tube or conduit, and by which the undue expansion of the tube is prevented.

The invention also consists in an expansible tube which in its normal condition is collapsed or in longitudinal folds, and which has embedded in it or incorporated between its inner and outer surfaces a spirally-wound re-enforcement of thread or cord, the convolutions of which are separated or isolated from each other lengthwise of the tube or conduit, and

which will collapse or fold with the tube, and which prevents the undue expansion of the tube.

In the accompanying drawings, Figure 1 represents a syringe having an expansible and collapsible or folding discharge tube embodying my invention. Fig. 2 is a perspective view, partly in section, of a portion of such expansible and collapsible tube. Fig. 3 is a transverse section of the tube in its collapsed condition. Fig. 4 is a corresponding section of the tube when expanded by pressure within it. Fig. 5 represents a portion of circular or cylindric tube in which my invention is embodied. Fig. 6 is a transverse section of such tube; and Fig. 7 is an exterior view of a bulb or enlarged portion of a tube also embodying my invention.

Similar letters of reference designate corresponding parts in all the figures.

A designates the discharge-tube of a syringe, having a bulb, B, whereby water may be discharged under pressure through the tube A, and a suction-tube, C.

The construction of the discharge-tube is best represented in Figs. 2, 3, and 4. This tube is of such construction that in its normal condition it is collapsed or folded, as represented in Fig. 3, so as to nearly or quite close the passage through it, and so that when liquid is forced through it under pressure it will readily expand to such form as is shown in Fig. 4, or to a greater degree. When the bulb is operated, the tube will be expanded and water will be discharged forcibly from the nozzle a, and when the bulb B is released from the pressure of the hand, so that it may recover itself, the excess of water which is contained in the expanded tube A will, by the collapsible force of the tube, be discharged in a nearly continuous stream from the nozzle, as is described in my aforesaid Letters Patent.

The tube A, to best perform its functions is made of quite thin and elastic india-rubber, and has embodied within it or incorporated between its inner and outer surfaces a spiral winding or re-enforcement, b, which is made of thread or cord, and which, by reason of its non-elastic nature, serves as a shield or guard

to prevent the tube from being expanded to such an undue degree as would render it liable to rupture.

The tube A may be made of two thicknesses 5 or plies of india-rubber, and after the cord or thread b is wound spirally upon the inner thickness or ply, the outer thickness or ply may be placed outside of the thread or cord and the tube afterward subjected to vulcanization. It will be observed that the convolutions of the spiral winding of the thread or cord b are separated considerably from each 10 other, and hence this spiral re-enforcement will not interfere materially with the longitudinal expansion or extension of the tube which may take place when in use. This spiral re-enforcement b affords ample protection against the expansion of the tube at any point to such an extent as would endanger rupture 15 and consequent leakage, and enables me to make the tube much thinner and more elastic than ordinary syringe-tubes, which qualities are highly desirable in a collapsible tube of the kind described.

20 In Figs. 5 and 6 I have represented a circular or cylindric tube, A*, having a spiral re-enforcement, b, which may be of thread or cord, and which, as before described, is embedded in the tube or incorporated between 25 two layers or plies of which it is formed. In this tube the convolutions of the spiral thread or cord are so far apart that opportunity is afforded for the expansion or bulging of the tube between such convolutions, and the spiral 30 winding will prevent any expansion which would be dangerous to the tube.

In Fig. 7 I have represented a syringe-bulb, A', which may be considered as an enlarged portion of the tube, and it has a spirally-wound 35 thread or cord, b, embodied in it or incorporated between its inner and outer surfaces. The bulb also may be made of two plies or thicknesses, between which the spiral winding of thread or cord b is applied before vulcanization, and in this bulb, as well as in the tube A*, the lateral expansion is confined to the 40 spaces between the convolutions of the re-en-

forcement b, and hence any such degree of expansion as would endanger the safety of the bulb is prevented.

50 In Figs. 5, 6, and 7 I have represented the thread or cord re-enforcement b by dotted lines, and have indicated its location by ribs upon the exterior of the tube and bulb.

I am aware that india-rubber dilators for 55 medical purposes have been provided with longitudinal inelastic cords or wires, which prevent their extension lengthwise and limit their expansion, so that it can act diametrically only. I do not claim such a dilator as 60 included in my invention. In my tube or conduit the re-enforcement or thread or cord is a spiral, the convolutions of which are so far separated or isolated one from another lengthwise of the tube that a limited diametrical ex- 65 pansion can take place between the convolutions, and the spiral cord or thread does not interfere with the lengthwise expansion or extension of the tube or conduit.

What I claim as my invention, and desire 70 to secure by Letters Patent, is—

1. An expansible tube or conduit having embedded in it or incorporated between its inner and outer surfaces a spirally-wound thread or cord, the convolutions of which are widely 75 separated or isolated from each other lengthwise of the tube or conduit, whereby the undue expansion of the tube or conduit is prevented, substantially as herein described.

2. An expansible tube which in its normal 80 condition is collapsed or in longitudinal folds, and which has embedded in it or incorporated between its inner and outer surfaces a spiral re-enforcement of thread or cord, the convolutions of which are separated or isolated from 85 each other lengthwise of the tube and which will collapse or fold with the tube and prevent its undue expansion, substantially as herein described.

BENJAMIN F. SUTTON.
